UNITED STATES PATENT OFFICE.

SAMUEL N. LONG, OF HARWICH, MASSACHUSETTS.

GAS-VALVE.

SPECIFICATION forming part of Letters Patent No. 642,618, dated February 6, 1900.

Application filed June 12, 1899. Serial No. 720,260. (No model.)

To all whom it may concern:

Be it known that I, SAMUEL N. LONG, a citizen of the United States, residing at Harwich, in the county of Barnstable and State of Massachusetts, have invented certain new and useful Improvements in Gas-Valves; and I do hereby declare the following to be a full, clear, and exact description of the invention, such as will enable others skilled in the art to which it appertains to make and use the same.

This invention relates to gas-valves; and it consists in the novel construction and combination of the parts hereinafter fully described and claimed.

In the drawings, Figure 1 is a plan view of the gas-valve. Fig. 2 is a side view of the same. Fig. 3 is a longitudinal section taken on the line $x-x$ in Fig. 1.

A is the casing of the valve, provided with gas-passages a' and screw-threaded end portions or nipples of approved construction.

B is the plug-valve, which is journaled in the casing and which has a gas-passage b , which connects the passages a' when the valve is open and disconnects them when the valve is closed.

C is a cylindrical extension at the top of the casing around the plug. This extension has a notch c in one side of it. D is a projecting boss on one side of the casing A.

E is a plate or disk which is secured to the top of the plug B and provided with a curved slot e , a finger-piece or projection e' , and two pins f on its lower side near its periphery.

G is a spiral spring the outer end of which engages with the pins f and has its inner end

hooked into the notch c . This spring normally holds the plug in the closed position.

H is a thumb-screw which passes through 40 the slot e and engages with the boss D.

The valve is opened to any required extent by moving the disk in the direction of the arrow in Fig. 1, and the thumb-screw is then screwed up, so as to hold the plug from being 45 moved backward by the spring. When the thumb-screw is unscrewed, the spring closes the valve automatically.

What I claim is—

1. In a gas-valve, the combination, with a 50 valve-casing, and a plug-valve journaled therein; of a plate secured to the plug-valve and provided with a slot, a spring connected to the said plate and casing and operating to close the valve, and a thumb-screw passing 55 through the said slot and connected with the casing, substantially as set forth.

2. In a gas-valve, the combination, with a valve-casing provided with a boss on one side and a cylindrical extension at its top having 60 a notch in one side of it, and a plug-valve journaled in the said casing; of a plate secured to the plug-valve and provided with a slot, a spring connected to the said plate and casing and operating to close the valve, and 65 a thumb-screw passing through the said slot and engaging with the said boss on the casing, substantially as set forth.

In testimony whereof I affix my signature in presence of two witnesses.

SAMUEL N. LONG.
